UNITED STATES PATENT OFFICE.

JOHN J. FERRALL, OF RIDGEWOOD, NEW JERSEY, ASSIGNOR TO NATIONAL BISCUIT COMPANY, OF NEW YORK, N. Y., A CORPORATION OF NEW JERSEY.

CONTAINER.

1,399,948.

Specification of Letters Patent. Patented Dec. 13, 1921.

Application filed July 16, 1920. Serial No. 396,656.

To all whom it may concern:

Be it known that I, JOHN J. FERRALL, a citizen of the United States, residing in Ridgewood, county of Bergen, and State of New Jersey, have invented certain new and useful Improvements in Containers, of which the following is a specification.

My invention relates to containers and particularly to boxes having glass or other transparent panes therein for the display of articles contained in the box such as crackers or other food products.

The chief object of my invention is to provide a structure in which a pane of glass or the like may be removably mounted in position to cover an opening in a display container in such manner that the same may be readily removed for the purpose of cleaning and the like, readily replaced and securely held when in position. Other objects of my invention consist in the details of construction and combinations of parts hereinafter more fully set forth in the specification and the accompanying claims.

In accordance with my invention the front of the box is provided with a window opening and with a horizontal cross piece spaced inwardly from the inner surface of the front above the opening. Short lugs are provided at the bottom spaced inwardly from the front, and the transparent pane may be inserted in position between the front of the box and the cross piece and lugs referred to. A movable abutment normally extends into

position above the top of the pane to prevent upward movement of the same and therefore to hold the same in position. When the pane is to be removed this abutment is moved inwardly so that the pane may be moved upwardly sufficiently to permit its lower edge to be withdrawn over the lugs at the bottom. The movable abutment referred to is preferably carried by a flat spring which is secured on the inner face of the cross piece and is pressed thereby into position above the pane. Preferably a slidable member is provided to co-operate with the spring and the cross piece, this member being movable to withdraw the abutment from operative position and to hold the same out of the path of the pane.

In order that a clearer understanding of my invention may be had attention is hereby directed to the accompanying drawings forming part of this application and illus-

trating one embodiment of my invention. In the drawings Figure 1 represents a front elevation of a container embodying my invention, Fig. 2 represents a partial, enlarged, rear elevation of the front member of the container, showing my invention, the sides and bottom of the container being shown in section, Fig. 3 is a horizontal section taken on line 3—3 of Fig. 2, Fig. 4 is a view similar to that shown in Fig. 3 but with the top abutment shown in operative position, Fig. 5 is a vertical section taken on line 5—5 of Fig. 2 and Fig. 6 is a vertical section taken on line 6—6 of Fig. 2.

Referring to the drawings, I have illustrated a container or box which is preferably formed of sheet metal, having a front 1, bottom 2, sides 3, 3, and a top 4. There is also, of course, a rear side which is not shown.

The front 1 of the box is provided with a window opening 5 which is preferably formed in the lower half of the front. A similar opening 6 may be formed in the upper half of the front, the metal of the front surrounding the openings 5 and 6 preferably being beveled inwardly as is shown at 7 and 8. The upper opening is intended to receive a name plate 9 and the lower opening is intended for the display of the goods and is covered by a pane 10 of glass or other suitable transparent material.

The opening 5 may, of course, be formed in any of the sides or surfaces of the box and I will refer, in the claims, to this opening as being formed in a side member, which should be understood as covering any one of the sides or surfaces of the box.

A cross piece 11 is provided above the opening 5 on the inner face of the front member 1, this cross member preferably extending all the way across the front. Cross piece 11 is spaced somewhat inwardly from the front 1 and preferably has a horizontal top flange 12 extending into contact with 100 and secured to front 1. This cross piece 11 may be soldered or otherwise suitably secured at its ends to the sides 3, 3 of the box and the forward edge of the horizontal flange 12 may similarly be secured to the 105 front 1 of the box.

A pair of short upwardly extending lugs 13, 13 are soldered or otherwise suitably secured to the bottom 2 of the box, inwardly from the front and in approximate vertical 110

alinement with the vertically positioned cross piece 11.

The top abutment for the pane 10 preferably takes the form of a horizontal lug 14 which is secured to or integral with the lower edge of a flat spring strip 15. The latter is secured at one end, as shown at 16, to the inner surface of cross piece 11. The flat spring may be held in position by any suitable means, as by slotting and bending slightly the metal of cross piece 11 to form a strap or pocket 16 under which the end of the spring is inserted, in which position the end of the spring may be soldered to the cross piece 11.

The abutment or lug 14 is adapted to move in a short horizontal slot 17 which extends through the cross piece 11. The lug or abutment 14 is preferably provided with an upturned flange 18 at its forward edge, to prevent the entire withdrawal of lug 14 from the slot in which the same is mounted. The free end 19 of flat spring 15 may be bent inwardly somewhat so that the same may readily be grasped to move the spring inwardly of the box. The spring pressure of member 15 tends to cause the member to lie flat against the inner face of cross piece 11 with the lug or abutment 14 positioned above the top edge of pane 10.

With the construction described a pane may be mounted in position by holding spring 15 in its inward position, sliding the upper edge of the pane inwardly between front 1 and cross piece 11 until the lower edge of the pane is above the tops of lugs 13 whereupon the pane is dropped into position with its lower edge between the bottom portion of front 1 and the lugs 13. The pane is now held in position by the lug 14 which is in position to prevent upward movement of the pane. When the pane is to be withdrawn the spring and lug 14 are again moved inwardly of the box and the pane raised sufficiently to permit its lower edge to clear the tops of lugs 13, the horizontal flange 12 being a sufficient distance above the top of the pane to permit this movement.

As a further improvement, I prefer to provide a device for moving the spring inwardly and holding the same in its inward or inoperative position. This preferably takes the form of a sliding member 55 which will coact with the spring and the surface of the cross piece 11 to wedge or cam the spring inwardly.

In the form of my invention illustrated this sliding member takes the form of a small sleeve 20 slidably mounted on spring 15. This member has a forwardly directed flange 21 which normally extends through a short horizontal slot 22 in cross piece 11. Flange 21 is provided with a curved or cam shaped surface 23. When it is desired to

withdraw abutment 14 from its operative position the sleeve or rider 20 is moved to the left, referring to Figs. 2, 3 and 4, by the finger of the user whereupon the surface 23 of flange 21 will ride up out of its slot and engage the surface of cross piece 11 in horizontal alinement therewith as is shown in Fig. 4. Spring 15 and abutment 14 will then be held in inoperative position until sleeve 20 is again moved to the right to cause flange 21 to drop into slot 22. The vertical inner edges of the sleeve 20 may be flanged inwardly or beaded as is shown at 24, to form surfaces which may readily be grasped by the hand of the user.

It should be understood that my invention is not limited to the details of construction described but is as broad as is indicated by the accompanying claims.

What I claim is:

1. In a container, the combination of a side member having an opening therein with a cross piece above the opening having a horizontal slot therethrough, and spaced inwardly from said side member, a seating surface below said opening with lugs spaced inwardly from said side member, said cross piece and lugs being adapted to engage the inner surface of a transparent pane mounted between the same and said side member, a top abutment movable through said slot into and out of position to prevent upward movement of the pane, said abutment having a flange thereon to prevent entire withdrawal thereof from the slot, spring means pressing said abutment through said slot into operative position, and manually operable means movable into position to move said abutment out of operative position, and holding the same in such position.

2. In a container, the combination of a side member having an opening therein with a cross piece above the opening, having a horizontal slot therethrough, and spaced inwardly from said side member, a seating surface below said opening with lugs spaced inwardly from said side member, said cross piece and lugs being adapted to engage the inner surface of a transparent pane mounted between the same and said side member, a top abutment movable through said slot into and out of position to prevent upward movement of the pane, a flat spring secured at one end on the inner face of said cross piece, carrying said abutment and pressing the same through said slot into operative position, means for preventing entire withdrawal of said abutment from said slot, and means coacting with said spring for holding said abutment, when moved to inoperative position, in such position.

3. In a container, the combination of a side member having an opening therein with a cross piece above the opening, spaced inwardly from said side member, a seating

surface below said opening with lugs spaced inwardly from said side member, said cross piece and lugs being adapted to engage the inner surface of a transparent pane mounted 5 between the same and said side member, a top abutment movably mounted adjacent to said cross piece, a flat spring secured on said cross piece, carrying said abutment, and tending to press the same into position 10 to prevent upward movement of the pane, slideable means adapted to coact with said spring and cross piece, movable into position to move said abutment out of operative position and hold the same in such position.

15 4. In a container, the combination of a side member having an opening therein with a cross piece above the opening having slots therethrough, lugs adjacent the lower edge of the opening, said cross piece and lugs being spaced inwardly from said side mem-

ber and adapted to engage the inner surface of a transparent pane mounted between the same and said side member, a top abutment movable through one of said slots into and out of position to prevent upward movement 25 of the pane, a flat spring carrying said abutment and pressing the same into operative position, and a cam member slidably mounted on said spring, normally positioned in a second one of said slots and movable therefrom into contact with the inner surface of 30 said cross piece, to move said abutment out of operative position.

This specification signed and witnessed this 30th day of June, 1920.

JOHN J. FERRALL.
